WINDOW SASH

Filed Jan. 31, 1927

William Inventor
Klocke

By Chas J. Murphy
Attest.

UNITED STATES PATENT OFFICE.

WILLIAM H. KLOCKE, OF WOODHAVEN, NEW YORK, ASSIGNOR TO KALMAN STEEL COMPANY, OF CHICAGO, ILLINOIS, A CORPORATION OF DELAWARE.

WINDOW SASH.

Application filed January 31, 1927. Serial No. 164,858.

My invention relates to window sashes and particularly to a novel method of manufacturing the same. It has for its object the production of a sash that will possess unusual strength and rigidity.

The weak joint in metal sash construction has heretofore been the joint or junction between the longitudinal and lateral members or mullions.

10 In my construction, I obviate the common defects by constructing the sash units of integral form, each unit comprising a continuous longitudinal member and integral lateral members having the same or similar 15 cross sectional shape as the longitudinal member. The units are so designed as to be adapted for production by rolling, thus materially reducing the cost of manufacture and assuring a structure of uniform strength and 20 rigidity.

The sash and the method of construction will be better understood by reference to the accompanying drawing in which;

Fig. 1 is a plan view of a unit in the form 25 in which it comes from the rolls;

Fig. 2 is a sectional view on the line 2—2 of Fig. 1;

Fig. 3 is a plan view showing a subsequent stage in the production of the unit; the web 30 of metal having been removed, the lateral arms bent outwardly and the end of the arms having been forged to provide for attaching tongues for an adjacent unit, one of such units being shown in dotted lines in that 35 figure.

Fig. 4 is a detail showing the method of attachment of adjacent arms, and;

Fig. 5 is a sectional view on the line 5—5 of Fig. 4.

40 The first step in the production of the sash is that of rolling a blank into the form shown in Figs. 1 and 2. In that form the longitudinal member A is continuous and of the cross-sectional shape shown in Fig. 2.

45 The member is generally T-shaped in cross section, comprising a web, 10, having a head, 11.

Inasmuch as it is impossible to roll a structure and eliminate all the metal between the

rolls, there will be left a web indicated at 12, 50 at the meeting line between the pair of rolls.

The next step is that of cutting out the web of metal which may be quickly accomplished by any suitable means. The next step is that of bending the lateral arms, which 55 are indicated at B, into a position perpendicular to the longitudinal member A. The arms are shown to be of the same cross sectional shape as that of the longitudinal members and comprise a web, 13 and a head, 14. After 60 the arms are bent into the position shown in Fig. 3, the web portions thereof at their ends are forged to provide a recess 15 and a tongue 16, the tongue representing the metal displaced in forming the recess. Thereafter, 65 two units similarly constructed are associated, with the tongues and recesses in interlocking engagement, and the overlapped portions are welded as at 17, in Figs. 4 and 5. In that position the head, 14, of the lateral members, 70 are in abutting engagement, the web portions only being overlapped.

A sash constructed in the manner described will be found to be extremely rigid and as there are no joints at the intersections of the 75 mullions, the structure will have exceptional strength. A sash may therefore be constructed having the required strength and rigidity by the use of less weight of metal.

The shape of the members constituting the 80 sash units is not important and variations in the shape and in the manner of attachment of adjacent units may be made without departure from the spirit of my invention.

I claim:

1. A window sash comprising in combination a continuous longitudinal member and integral laterally projecting arms, and means for joining a plurality of so-formed units by overlapping engagement at the ends of 85 said arms.

2. In combination, a widow sash composed of a plurality of units each unit consisting of a continuous longitudinal member and integral lateral arms, the arms of a plurality 90 of said units being brought into register, and means for joining overlapping portions of said registering arms.

3. In combination, a window sash composed of a plurality of units, each unit consisting of a longitudinal member and integral perpendicular arms, the member and arms being of similar cross-sectional shape, the ends of the arms being shaped to provide a tongue adapted to overlap the end of a

registering arm on an adjacent unit, and means for joining said registering arms by means of said overlapping projections. 10

In testimony whereof, I have affixed my signature.

WILLIAM H. KLOCKE.
